UNITED STATES PATENT OFFICE.

OTTO A. FREDERICKSON, OF WETHERSFIELD, CONNECTICUT, ASSIGNOR TO THE WIRE-MOLD COMPANY, OF HARTFORD, CONNECTICUT, A CORPORATION OF CONNECTICUT.

ELECTRICAL CABLE.

Application filed September 7, 1926. Serial No. 133,959.

This invention relates to a novel insulating material for electrical conductors.

Insulated electrical conductors as now extensively employed in wiring buildings for electric light circuits and for other purposes, are commonly formed of a metallic conductor about which a jacket of rubber is provided and over the rubber jacket is braided or woven a tubular covering. This tubular covering 10 may in turn be protected by a metallic or non-metallic outer jacket.

The rubber jacket possesses good insulating properties but does not afford good mechanical protection and the braided or woven covering is therefore relied upon to protect the rubber jacket from injury and also to increase the electrical protection of the conductor. This protecting covering should therefore be made of strong, durable, non-20 conducting material, and the cost of such covering should be as low as other requirements will permit.

The present invention therefore contemplates the use of a novel material in forming 25 a protecting covering for electrical conductors, and which possesses various advantages over the cotton and other spun fibres commonly employed heretofore in the construction of such covering; and in accordance with 30 the present invention the insulating covering which may be braided or woven is formed, at least in part, of narrow strips of paper that may be cut from a sheet of tough, relatively 35 thick paper and introduced directly into the tubular fabric without being previously twisted or folded.

A protecting covering formed of these narrow, untwisted strips of paper is extremely tough and durable, possesses excellent insulating properties, and may be constructed at 40 very low cost.

The various features of the present invention will be best understood from the following description when read in connection with 45 the accompanying drawings, illustrating one embodiment of the invention:

In the drawings:—

Fig. 1 is a perspective view of an insulated electrical cable embodying the features of 50 the present invention;

Fig. 2 is a transverse sectional view of Fig. 1;

Fig. 3 on an enlarged scale is a perspective view of one of the insulated conductors of Fig. 1;

Fig. 4 is a transverse sectional view of Fig. 3; and

Fig. 5 is a perspective view of a paper strip employed in the construction of the insulating covering.

An insulating covering constructed in accordance with the present invention may be employed in the manufacture of different types of insulated electrical cable, and is shown in the drawings as applied to a two-conductor cable adapted for use in wiring buildings for the installation of electric lights. Each of the conductors 10 of this cable is provided with an insulating jacket 11 that may be formed of rubber. About 65 each jacket 11 is provided a protecting covering 12 which is shown as formed of braid constructed in accordance with the present invention.

About the braid 12 of each conductor, in 75 the construction shown, is wrapped a series of strands 13 placed spirally about the braid, and the insulated conductors thus formed are enclosed and united by the outer jacket 14. The fillers 15 are laid in the valleys at the 80 opposite sides of the conductors to fill up the air spaces between the conductors and outer jacket.

In electrical cables of the type shown in Fig. 1 of the drawing the construction of the 85 first layer 12 is particularly important, because this layer should furnish the maximum of protection to the rubber jacket 11 while at the same time its size should be kept down to the minimum, and this layer should be sufficiently flexible to withstand sharp bends 90 without injury and without causing substantial openings to occur between the strands forming the layer. Furthermore, the strands of which the layer 12 are formed should be 95 so interwoven or braided that they will not unravel when the cable is cut.

The above requirements are well met when the layer 12 is constructed in accordance with the present invention, and in carrying out 100

this invention the layer 12 is made up of the paper strands 16 that extend about the conductor 10 in one direction and are interbraided with the strands 17 that extend in the opposite direction.

The strands 16 constitute untwisted and unfolded strips of paper which may be cut from a sheet of high quality stock paper having the desired toughness and a thickness that is equal to the thickness of the strips 16 into which the sheet is cut. The width and thickness of the strips 16 may of course be varied as desired, but it has been found from experience that strips of paper .015" in thickness by .02" in width produce a satisfactory covering for the rubber jacket 11.

A sheet of paper having the desired thickness and tensile strength can be cut with a high degree of accuracy and without waste into narrow strips 16 of the desired width, and these strips can be taken directly from the slitting machine and wound on tubes ready for use in a braiding machine or circular loom. The binding strands 17 may be formed of cotton and are smaller and more flexible than the paper strands so that they readily bend around the paper strands and bind the paper strands in place side by side in edge contact with each other to form an extremely tough and durable protecting covering.

If desired the outer jacket 14 may also be formed of a braid made up of untwisted paper strands 16 that are interbraided with the binding strands 17, and in some cases the spirally wound strands 13 may also be formed of narrow strips of paper.

It will be apparent from the foregoing that the untwisted and unfolded strips of paper 16 may be easily and quickly produced by a single operation, since all that is necessary

is to cut the strips 16 having the desired width from a sheet of tough, strong stock paper having the required thickness.

What is claimed is:—

1. A protecting jacket or covering for electrical conductors formed of narrow untwisted and unfolded strips of tough paper that are cut from a sheet of paper having the thickness of the individual paper strands forming the braid and which are interbraided with binding strands to form a tubular jacket or covering. 45

2. A protecting jacket or covering for electrical conductors formed of narrow, untwisted and unfolded strips of tough paper that are cut from a sheet of paper having the thickness of the individual paper strands of the jacket or covering and which are interlocked with binding strands to form a tubular jacket or covering. 55

3. An insulated electrical conductor, comprising a metallic conductor having a protecting jacket of tubular fabric formed of intermeshing strands one set of which strands is formed of narrow untwisted and unfolded strips of tough paper that are cut from a sheet of paper having the thickness of the individual paper strands embodied in the fabric. 65

4. A protecting jacket or covering for electrical conductors formed of narrow untwisted and unfolded strips of tough paper that are cut from a sheet of paper having the thickness of the individual paper strands embodied in the jacket or covering and which are held side by side in edge contact with each other by smaller and more flexible binder strands to form a tube. 70

In testimony whereof, I have signed my name to this specification.

OTTO A. FREDERICKSON.
